U. G. LEE

LIQUID HEATING DEVICE

Filed April 18, 1923

Inventor:
Ulysses G. Lee,

by Spear Middleton Donaldson Hall
Atty's.

UNITED STATES PATENT OFFICE.

ULYSSES G. LEE, OF CHICAGO, ILLINOIS.

LIQUID-HEATING DEVICE.

Application filed April 18, 1923. Serial No. 632,922.

My present invention relates to improvements in heat generators for heating fluid by mechanical action or agitation and aims to provide a construction in which the temperature regulation will be automatic, but which may be adjusted or set to generate to any predetermined or desired temperature.

With these and other objects in view, the invention includes the novel features of construction and arrangement and combination of parts hereinafter described and particularly defined by the appended claims.

In the accompanying drawings:—

Fig. 1 is a sectional elevation, largely of a diagrammatic nature, showing one embodiment of my invention.

Fig. 2 is a similar view, showing it as adapted to heat the combustible mixture supplied to an internal combustion engine.

Referring by reference characters to these drawings, the numeral 1 designates a closed container for holding the fluid to be heated, which may be provided with a steam dome 1^a, from which steam may be drawn when the device is only used for a steam generator. A rotary shaft 3 is journaled in the container walls and is designed to be driven at high speed by any suitable means, for example belt pulley 3^a.

Shaft 3 carries agitating means such as spaced radial blades 3^b designed to cooperate with alternating spaced blades 1^c rigidly carried by the container walls. A pipe 4 connects the lower part of the container, preferably the bottom, with the lower part of an expansion chamber 6 having filling means, such for example as nozzle 6^a, preferably located at such a point as to preserve an air space above the normal liquid level

shown. The expansion chamber may be provided with a pressure gage indicated at 12, and means are provided for introducing additional air into the chamber 6 to increase the air pressure above the liquid, which means may take the form of an air pump 13.

In the operation of the device above described, the violent agitation of the liquid in container 1 heats it in the manner well understood by those skilled in the art, until the generation of steam in the container causes pressure above the surface of the liquid, forcing some of the liquid out into the expansion tank, thus lowering the level in the container 1, until more or less of the blades and baffles project above the surface

of the liquid, which decreases the heating effect of the agitator. If the temperature drops, the steam condenses and the liquid level rises, whereby the heating effect is increased.

To cause the heater to raise the temperature above normal boiling point, it is only necessary to pump additional air into the expansion chamber, which increases the pressure and retards the lowering of the liquid level in the container 1.

In the form shown in Fig. 2, in which the apparatus is applied to heating the combustible mixture of an internal combustion engine, the container is shown as secured to the engine block 2 and the shaft 3 is driven from the engine in suitable manner, as by bevel gears 3^d and 3^e.

The interior of the container is connected by the flow and return pipes 4^a and 4^b with a closed annular fluid chamber 6^a surrounding the fluid intake 7 of the engine, the connection of one of the pipes (4^b for example) being preferably made through an auxiliary heating chamber 8 surrounding the exhaust pipe 9. The chamber 6^a is provided with a filling nozzle 6^x capable of being hermetically closed by a removable filling cap 6^y, the filling nozzle being located at such a height that a certain amount of air will be entrapped in the system after the remainder thereof has been filled, as indicated by the water level shown in the drawing.

Preferably cross tubes 6^b are provided in the lower part of the chamber which extend through the intake chamber 7 and increase the heating effect.

The circulating pipe 4^a which carries the fluid away from the heater connects to the container at a point opposite the lower paddle wheel and tangent to the outer circumference of the wheel after the manner of a centrifugal pump, while the return flow pipe 4^b connects near the center of the wheel.

This arrangement causes a forced circulation which is necessary, as the circulation from gravity is very sluggish; also it makes it possible to force the circulation to a point below the level of the heater when so desired, which would be impossible if gravity alone was the circulation means.

Means similar to that shown in Fig. 1 are provided for introducing additional air into the system to increase the pressure of the air above the surface of the liquid in the con-

tainer, which may take the form of an air pump 13^a, shown conventionally.

A pressure gage may be provided, as indicated at 12.

5 In the operation of this form of my apparatus, the engine having been started, the violent agitation of the liquid quickly heats the same and the heated fluid circulates through the heating chamber 6^a, thus heating 10 the combustible mixture passing through the intake pipe.

When the liquid has been heated to the point of generating steam, pressure of the latter, accumulating in the top of container 15 1, will lower the level of liquid in the container and expose some of the paddles, which will decrease the mechanical heating effect, and thereafter the temperature of the fluid will be automatically maintained.

20 Should it be desired to heat the liquid above the normal boiling temperature, additional air may be introduced into the system, thus increasing the air pressure above the liquid in chamber 6, which would require 25 a corresponding higher steam pressure in container 1 to uncover any of the agitator blades.

After the engine has been operated for a material length of time, the exhaust pipe 30 heats up and the heat thereof is imparted to the fluid by auxiliary heater 8.

I have found that such an exhaust heater is sufficient when the engine is run on an open throttle, but not when on a closed or 35 partly closed throttle, the temperature of the exhaust pipe varying under operating conditions.

By my construction I utilize the heat of the exhaust pipe where this is sufficient, but 40 when not sufficient, and the temperature of the liquid drops below the predetermined temperature, the mechanical heater automatically operates to raise it to and maintain it at the desired temperature.

Having thus described my invention, what 45 I claim is:—

1. In a fluid heating system, the combination with a pipe containing the fluid to be heated, of an hermetically closed chamber surrounding said pipe, an hermetically 50 closed mechanical liquid heater, and pipe connections therefrom to said closed chamber, the pipe connections between said chamber and heater being so arranged that the mechanical action of the heater causes a 55 forced circulation through said connections.

2. The combination with an hermetically closed liquid heating chamber, of a mechanical agitator located therein and comprising a series of agitating blades arranged at 60 varying elevations, means for operating said agitator, and an hermetically closed expansion tank connected with the lower portion of said heating chamber, said tank and the quantity of liquid therein being so arranged 65 and proportioned that steam pressure in said heating chamber causes liquid to be expelled into the expansion tank, thereby uncovering more or less of the agitator blades and reducing the heating action. 70

3. The combination with an hermetically closed liquid heating chamber, of a mechanical agitator located therein and comprising a series of agitating blades arranged at 75 varying elevations, means for operating said agitator, and an hermetically closed expansion tank connected with the lower portion of said heating chamber, said tank and the quantity of liquid therein being so arranged 80 and proportioned that steam pressure in said heating chamber causes liquid to be expelled into the expansion tank, thereby uncovering more or less of the agitator blades and reducing the heating action, and means for varying the air pressure in said expansion 85 tank above the liquid level therein. 70

In testimony whereof I affix my signature.
ULYSSES G. LEE.
